CLAIM

The ornamental design for a gaucho grill with shallow tray, as shown and described.

DESCRIPTION

FIG. 1 is a front perspective view of a gaucho grill with shallow tray, showing my new design;

FIG. 2 is a top plan view thereof;

FIG. 3 is left side elevation view thereof;

FIG. 4 is a front elevation view thereof;

FIG. 5 is a back elevation view thereof; and,

FIG. 6 is bottom plan view thereof.

(Continued)

The evenly broken lines are shown for the purpose of illustrating parts of the article that form no part of the claim. The dot-dash lines represent the boundaries of the claim and form no part thereof.
